UNITED STATES PATENT OFFICE.

JOHN E. JERROLD AND CHRISTIAN L. BURGERMEISTER, OF ALLEGHENY,
ASSIGNORS OF ONE-THIRD TO THOMAS M. REES AND WILLIAM M.
REES, BOTH OF PITTSBURG, PENNSYLVANIA.

VALVE FOR ENGINERY AND VESSELS.

SPECIFICATION forming part of Letters Patent No. 300,373, dated June 17, 1884.

Application filed February 6, 1884. (No model.)

To all whom it may concern:

Be it known that we, JOHN E. JERROLD and CHRISTIAN L. BURGERMEISTER, both of Allegheny, in the county of Allegheny and State 5 of Pennsylvania, have invented a new and useful Improvement in Valves for Enginery and Vessels; and we do hereby declare that the following is a full, clear, and exact description thereof, reference being had to the accompanying drawings, and to the letters of reference marked thereon.

Our invention has for its object the construction of a valve having its seat located within a boiler, tank, or vessel which may 15 contain steam, air, gas, or liquid, the case of said valve being so arranged with relation to the boiler, tank, or vessel that that portion of the case projecting therefrom may be broken off without liability of the steam, air, gas, or 20 liquid escaping.

Our invention consists in so constructing a valve and its case or shell that the valve and its seat shall be within the boiler, tank, or vessel to which it may be applied, the stem 25 of said valve constructed in two parts, and the case or shell in one or more parts, said invention being applicable to steam, gas, air, and water enginery, and also to vessels for holding liquids; and said invention may be 30 applied in distinct articles of manufacture.

To enable others skilled in the art with which our invention is most nearly connected to make and use it, we will proceed to describe its construction and operation.

35 In the accompanying drawings, which form part of our specification, Figure 1 is a longitudinal section of our improvement in valves for enginery and vessels. Fig. 2 is a transverse section of the same at line A' B'.

40 In the drawings, A represents a section of a boiler with the shell of the valve secured therein, which shell consists of the parts C D E, secured together through the medium of screw-threads. (Clearly shown in Fig. 1.)

45 The valve B is of ordinary construction, excepting that its stem is constructed in two parts, (marked N I,) the part I having screw-threads J, which are fitted to screw-threads in the part marked K of the shell. At the 50 junction L of the parts N and I of the stem the ends form sections of a sphere. The valve

B is held to its seat by the pressure of steam or other force in the boiler or vessel. The stem has a hand-wheel, H, and the shell a capping and packing piece, G.

55 The construction of the valve and its stem, the valve-seat, and the shell of the valve, and their application to enginery are so clearly shown in the accompanying drawings that the skilled mechanic could readily construct 60 the same by reference to said drawings without any further description. We will therefore briefly describe the operation and advantages of our improvement in valves.

The valve is unseated by turning the hand-wheel H, which, through the medium of the screw-threads J on the part I of the stem, will cause said part at L to press against the part N at L, thereby forcing the valve B off its seat, and by reversing the action of the hand-wheel 70 the part I of the stem will be drawn back and the pressure of the steam will cause the valve B to be seated.

75 The advantage of the hereinbefore described construction of valve and its shell, and the application thereof to a steam-boiler or analogous use, consists in the fact that should that portion of the shell projecting from the exterior of the boiler be broken off by accident of any kind the valve B will remain 80 seated and prevent the escape of steam. Such construction will therefore be of very great advantage in locomotive and other enginery, for in almost every case of accident the escaping steam results in the scalding or death of 85 the engineer and others.

Having thus described our improvement, what we claim is—

The combination, with the three-part casing C D E, the former having the stem N, provided with the valve B and spring M, of the screw-threaded stem I, engaging the screw-threaded portion K, and passing through the parts D E, and resting on the top of the stem N, and the wheel H and packing-piece G, 90 substantially as shown and described, and for the purposes set forth.

JOHN E. JERROLD.

C. L. BURGERMEISTER.
